INVENTOR

BY *Victor J. Evans*
and Co. ATTORNEY

UNITED STATES PATENT OFFICE

CALVIN H. WIMBERLEY, OF NEW BRAUNFELS, TEXAS

ROD

Application filed October 19, 1931. Serial No. 569,765.

This invention relates to rods, and its general object is to provide a rigid rod constructed from hingedly connected links disposed in row formation, with a pair of rows interconnected to provide a rod which is rigid, with the result a rod of any desired length can be formed merely by adding the number of links necessary or desired.

A further object of the invention is to provide a rod of the character set forth, that is simple in construction, inexpensive to manufacture, and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a perspective view illustrating a rod constructed in accordance with the present invention and illustrates the manner of associating the links.

Figure 2 is a fragmentary top plan view.

Figure 3 is a sectional view taken approximately on line 3—3 of Figure 2.

Figure 4 is a top plan view of one of the links.

Referring to the drawing in detail the reference numeral 1 indicates a link which is formed from a strip of relatively flat thin material and is rectangular in formation, with a square cornered opening 2 disposed slightly beyond the transverse center of the body of the link as best shown in Figure 4.

Extending from one end of the body of the link and disposed centrally of said end is a barrel 3, while extending from the opposite end and centrally thereof is a tongue 4 extending in a plane parallel with the body as best shown in Figure 3. Arranged upon opposite sides of the tongue are barrels 5 and the barrels 5 are adapted to have disposed between the same a barrel 3 of a companion link as best shown in Figure 1, and when the

barrels 5 are aligned with a barrel 3 of the companion link, a pivot or hinge pin 6 is disposed within the aligned barrels for hingedly connecting a plurality of links together.

When the links are pivotally secured together it will be apparent that they provide a flexible chain and two of these chains are associated by disposing the tongues 4 through the openings 2, with the links arranged in contacting engagement and when so associated, there is provided a rigid rod which may be utilized for any desired purpose.

By forming the rod as above set forth, it will be obvious that the length of the rod will depend upon the number of links used, with the result any length rod may be made merely by adding or removing the links.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A device comprising a pair of opposed chains including links, each provided with an opening, cooperating hinge barrels formed with the links, means passing through the cooperating hinge barrels to hingedly secure the links together, and tongues formed with the links and being arranged in the openings of opposed links of the chains to secure the latter in contacting engagement with each other to provide a rigid rod.

2. A device comprising a pair of opposed chains each including substantially flat links having openings arranged therein, a single hinge barrel disposed at one end of each link, a pair of hinge barrels disposed at the opposite end thereof, the single hinge barrels being hingedly secured between the pairs of hinge barrels, and tongues formed with said links and extending in a plane parallel therewith, and said tongues being arranged in the openings of opposed links of the chains to secure the latter in contacting engagement with each other to provide a rigid rod.

3. A device comprising a pair of opposed

chains including links, each being provided with a flat elongated body having an opening disposed to one side of the transverse center thereof, a single hinge barrel extending centrally from one end of the body, a tongue extending centrally from the opposite end of the body in a plane parallel therewith, a pair of hinge barrels formed with said body, with the barrels of the pair disposed upon opposite sides of the tongue, said pairs of hinge barrels receiving the single barrels of companion links between the same for cooperation therewith, hinge pins arranged in the cooperating barrels for securing the links together, and the tongues arranged in the openings of opposed links for engagement with the latter to secure the chains in contacting engagement with each other to provide a rigid rod.

23 In testimony whereof I affix my signature.
CALVIN H. WIMBERLEY.
